FISHING BOBBER

Donald W. Betts, Fuquay Varina, N.C., assignor to
Frederick A. Lambach, Omaha, Nebr.

Filed Dec. 14, 1966, Ser. No. 5,025

Term of patent 14 years

(Cl. D22—30)

Fig. 1

Fig. 2

Fig. 3

Fig. 4

Fig. 5

Fig. 6

Fig. 7

FIG. 1 is a side elevation of a fishing bobber showing my new design;

FIG. 2 is a side elevation taken at ninety degrees from FIG. 1;

FIG. 3 is a top plan view of FIG. 2;

FIG. 4 is a bottom plan view of FIG. 2;

FIG. 5 is a side elevation of a modified form of the fishing bobber shown in FIG. 1;

FIG. 6 is a side elevation taken at ninety degrees from FIG. 5; and

FIG. 7 is a bottom plan view of FIG. 6.

I claim:

The ornamental design for a fishing bobber, substantially as shown and described.
